KNOT TIER

Edward J. Abbott, Wilton, N. H., assignor to Abbott Machine Company, Wilton, N. H., a corporation of New Hampshire

Application February 12, 1936, Serial No. 63,540

15 Claims. (Cl. 289—2)

This invention relates to mechanism for uniting strands, and although many features of the invention are applicable to knotters which are held or operated by hand, the invention attains its fullest utility as embodied in a mechanism for automatically uniting new supply bobbins to the yarn packages in a winding machine. By way of example the invention is herein illustrated and described as applied to a bobbin magazine and feeding mechanism associated with automatic package-end finding mechanism such as described in the patent application of Edward J. Abbott and Joseph Ring, for Winding machine, Serial No. 726,524, filed May 19, 1934.

Among the several objects of the invention is to provide an improved and more compact and simple knotter mechanism and particularly, although not exclusively, such a knotter mechanism of the kind having two cooperating tying bills. A further object is to improve and simplify the mechanism which acts to cross and guide the strands during the formation of the knot, the mechanism which strips or pulls off the knot from the tying mechanism and tightens the knot, and the mechanism for operating these parts in timed relation. A further object is to provide improved mechanism for initiating the actuation of a knotter, preferably in timed relation to the operation of means for causing strands to be presented thereto for tying. Another object is to provide an improved and simplified driving mechanism adapted to act very quickly but in a reliable manner to rotate the knotter through the required cycle of operation and stop and hold the knotter in position ready for its next operation. It will be understood that when embodied in automatic winding machines, the speed with which the knotter performs its function is of importance, since in large measure it determines the number of winding units on which the automatic tying mechanism can act in a given time, and hence the number of winding units which can economically be tended by the same knotter.

Other objects of invention and features of advantage and utility will be apparent from this specification and its drawings wherein the invention is explained by way of example. Many of the features of this invention claimed herein are also applicable to and shown as embodied in the mechanisms disclosed in the application of Edward J. Abbott for patent on Automatic winder, Serial No. 63,542, and in the application of Edward J. Abbott for patent on Knotter, Se-

rial No. 63,541, both filed concurrently herewith.

In the drawings:

Fig. 1 is a plan view, partly in section, of a rotary magazine for an automatic winder, showing a knotter mounted on the central suction column which holds the ends of strand in the magazine;

Fig. 2 is a view taken on a vertical plane, partly in section and partly in elevation, with certain parts broken away, showing the knotter, magazine and suction conduit of Fig. 1, and the mechanism for operating the knotter from the motion of the rotary magazine;

Fig. 3 is a side elevation of the knotter, with the cover for the knotter cam removed;

Fig. 4 is a side elevation of the yarn-guiding plate of the knotter, showing the yarn-crossing mechanism and knot-stripping arm mounted thereon;

Fig. 5 is a plan view of the knotter with the cover for the knotter cam removed;

Fig. 6 is a sectional view taken on line 6—6 of Fig. 5, showing a plate disposed in position to hold securely on the bills the pair of strands being knotted; and

Fig. 7 is a fragmentary plan view, partly in horizontal section, showing the action of the plate of Fig. 6 on the strands being knotted.

The present invention is shown as embodied in an automatic winding machine bobbin magazine having many of the features disclosed in the patent application of Edward J. Abbott and Joseph E. Ring for Winding machine, Serial No. 726,524, filed May 19, 1934. Also as disclosed in a patent application of Edward J. Abbott for Automatic winder, Serial No. 63,542, filed concurrently with the present application and disclosing many of the features of the present application, the invention of the present application is useful in a traveling magazine adapted to replenish the bobbin holders of stationary winding units of a multiple winding machine.

Referring particularly to Figs. 1 and 2, there is illustrated a central suction tube 14 within which the air is maintained under a reduced pressure by any suitable exhauster. One end of a slotted tube 15 extends within and is spaced from the inner wall of tube 14 by a suitable spacer member 16, and the other end of slotted tube 15 terminates in a suitable end-finding nozzle, indicated at 17, close to an unwinding roll 18, such as the rolls shown in the applications referred to above, the action of these parts being to find the end of strand on a package P 55

of a winding unit 70 with which the nozzle is associated, carry the found end in the tube 75 and its slot 124 across the space from the package to the top of the tube 74, and there hold 5 the found strand under tension in the knotter 125 later described.

A plate 97 rotatable about tube 74 forms the support for a series of cylindrical bobbin holders 98, each slotted at 99 and provided with a bottom 10 trapdoor 100. Any suitable means for rotating and controlling the magazine may be provided, for example a rotary disk 105, constantly driven through its internal gear teeth 107 from a suitably driven pinion 108, the plate 97 being restrained and controlled by latch and tripping mechanism such as disclosed in the above-mentioned application for patent on Automatic winder and thereby timed to rotate the magazine through an arc corresponding to one bobbin 15 holder 98 each time a new winding unit is encountered. Bobbins of replenishment strand are held in the bobbin holders 98, and the ends of strand of these bobbins are held by suction in the tube 74. Rotation of the magazine brings 20 the replenishment strands successively to the knotter 125, a replenishment strand arriving at the knotter at the same time that the tube 75 delivers to the knotter a found end of strand of the package of a winding unit.

30 A rim 112 on a stationary flange 110 supports the trapdoors 100 of the bobbin holders 98 but terminates at a point opposite to the knotter 125, there allowing the trapdoor 100 to drop to a vertical position and discharge the replenishment 35 bobbin which has been tied by the knotter to the found end of strand.

Referring particularly to Figs. 3 to 7 inclusive, the knotter 125 herein illustrated preferably is arranged and constructed to tie the knot described in United States Letters Patent No. 1,965,023, namely a knot in which each of a pair of strands is formed into a knot around only one thickness of the other strand, the two such single knots being drawn together so as to reinforce 40 each other against displacement of the combined knot by tension in the united strand. Certain aspects of the invention are not limited to the tying of that kind of knot, and certain claims of this application are generic to the mechanism of the patent application of Edward J. Abbott 45 for Knotter, Serial No. 63,541, filed concurrently herewith.

As illustrated in Figs. 3 and 5, the knotter includes a U-shaped frame member 200 on the side elements 201, 202 of which there are mounted 50 a main drive shaft 137 and a pair of coaxial rotary tying bills 130, 131, connected by gearing 133, 134 and 135, 136 so as to be rotated by the shaft 137. This main shaft 137 carries a notched friction plate 138 contacted by friction material 140 (Fig. 1) on the face of a rotary drive element 139 which is pressed against the plate 138 by a spring 141. The rotary drive element 139 is constantly driven through gear teeth 142 on its periphery (Fig. 2) by a train of gearing 143, 144, 55 145 from the shaft 146 of an electric motor 126. The knot tier 125 and motor 126 are conveniently supported by a bracket 127 mounted on the suction tube 74.

60 A pivotally mounted latch 147 normally engages the notched plate 138 and restrains it and the knotter shaft 137 against rotary movement by the constantly running driving motor 126, the latch 147 restraining the shaft 137 at such a 65 position that the bills 130, 131 and other movable

strands-engaging parts of the knotter are at their initial or starting positions of Figs. 3 and 5, ready for the reception by the knotter of a pair of strands to be tied.

As the magazine rotates and brings a new replenishment strand into the knotter, one of a series of projections 151 on the plate 97 of the magazine lifts a pivotally mounted element 152 (Fig. 2) and raises a lifter rod 153 attached thereto and to the latch 147, thereby disengaging 10 the notched plate 138 and permitting this plate and the knotter shaft 137 to be turned through one revolution by the knotter-driving mechanism. Upon the conclusion of one revolution of the shaft 137, which produces two full revolutions of the bills 130 and 131, the latch 147 drops into engagement with the shoulder of the notched plate 138 thereby restraining the knotter parts against movement past their initial or starting position shown in Figs. 3 and 5. The continuous frictional effect of the friction material 140 of driving disk 139 upon the plate 138 insures that the knotter parts will be held in their initial position, ready to receive the next pair of strands to be united.

25 A side plate 180, associated with the U-shaped frame element 200, serves as a guide and positioning member for the pairs of strands to be united. One strand, from a replenishment bobbin in one of the bobbin holders 98, is slid by 30 the rotary movement of the magazine along a smooth upper surface 180^a of the plate 180 until it drops into a slot 199 adjacent to the bill 130, and the other strand of the pair is laid by the suction tube 75 into a second slot 197 adjacent 35 to the bill 131 and in spaced relation to the strand in slot 199. Each of these slots 199 and 197 is rounded at its mouth to facilitate the entrance of its strand.

40 A further guide member 181 on the opposite side of the bills upon the slots 199, 197, is shaped to cooperate therewith in holding the strands in position for tying. This guide member 181 is in the form of a metal strip of which the side edges diverge from a top point 198 to a pair of shoulders 183, 184 beneath which the strands are 45 adapted to thread, and which act to hold the strands down in position for tying.

The strand-crossing mechanism which arranges the strands for tying is shown in Fig. 4 as including a pocket 158^a carried by a member 50 185 which is pivoted to the plate 180 at 186, and a pocket 158^b carried by a link 187 which is slotted at 188 so as to slide on the pivot 186. A pin 191, fast on member 185 and engaging in a slot 192 in link 187 acts to swing member 185 in a 55 clockwise direction about the pivot 186 when link 187 is shifted to the left. A lever 182, pivoted to the plate 180 at 181 is connected at its upper end by a pivot 188 to link 187 and carries a cam follower 183 which engages a cam groove 157 in a cylindrical cam 156 which is fast on the main shaft 137. The cam groove 157 is so shaped that one revolution of the main shaft initially crosses the strands in the path of the bills, then, after the crossed strands have been picked up by the bills, returns the pockets 158^a and 158^b to their initial positions of Figs. 3, 4, and 5 while the bills are making their first revolution, and retains the pockets in this position throughout the remainder of the knot-tying cycle.

70 Each bill 130, 131 is provided with the usual fixed blades, and also with a pivoted clamping shear blade, 130^a and 131^a respectively, best shown in Figs. 5 and 7. Pivoted blade 130^a is 75

provided with cam-follower extensions 130^b and 130^c adapted to engage a stationary cam strip 40, and pivoted blade 131^a is provided with cam-follower extensions 131^b and 131^c adapted to engage a stationary cam strip 41, the effect of these cams and cam-followers being to open the pivoted blades as the bills point downwardly and to close the blades as the bills turn from a downward position to the position of Fig. 3.

10 The manner of tying the knot in the crossed strands will be apparent from the aforementioned United States Letters Patent No. 1,965,023 and need not be further discussed herein except to point out that the bills turn in the direction of the arrow X in Fig. 6 and that at the end of approximately three-quarters of a revolution of the bills, as indicated in Fig. 7, the bills are swinging upwardly and are each carrying a complete loop of one strand which has also been bent about the 20 opposite bill and a bend or partial loop of the other strand which has also been formed into a complete loop about the opposite bill. Thus both strands extend across between the two bills, as indicated in Fig. 7, and the two portions of strand destined to become the knot tails are about to be picked up between the fixed and pivoted blades of the bills, to be clamped and severed. Further rotary movement of the bills through about 90° from the position of Fig. 7 to the initial position 30 of Figs. 3 and 5 will result in the knot tail portions being clamped and severed. At the stage represented by Fig. 7, the two portions of the strands destined to form the tails of the knot are still engaged under the shoulders 183, 184 of the 35 guide member 181, and are under the tension imparted to them by the suction in the tube 74.

As the pivoted blades close, it is desirable to prevent the tension in the strand and the rotary movement of the bills from prematurely casting off the knot-formation which has been set up in the form of Fig. 7. Moreover, it will appear from Fig. 7 that the position of the two laterally extending portions of strand which extend across from one bill to the other will determine the 45 length of the knot tails, for if these laterally extending portions are near the tips of the bills the knot tail portions will be cut off close to them, whereas if these laterally extending portions are close to the axis of rotation of the bills, the knot tail portions will be cut longer. The present invention preferably provides a guard member 43 extending from the guide element 181 in between the bills in a part of their rotary movement, thus to provide a curved, a generally arcuate edge 44 upon which the two laterally extending portions 50 of strand can run, and which thereby prevents the premature casting off of the knot-formation and also determines the position of these laterally extending portions with reference to the bill axis and so regulates or determines the lengths 55 of the tail portions of the knot. As indicated in Fig. 6, the guard element 43 terminates at a point a little past the upright position of the bills, so as to permit the knot-formation to be pulled off the bills toward the side opposite to the guide member 181.

A knot-stripping or pull-off arm 160 is shown as pivoted at 193 to the plate 180 so as to operate in a plane substantially parallel thereto, and carries a cam follower 194 which engages a cam groove 159 in the cam 156. The shape of cam groove 159 is such as to keep the pull-off arm 160 idle in approximately its full-line position of Figs. 3 and 4 until almost the end of the first 70 full revolution of the bills, and then to lift the

pull-off arm quickly to the dotted position of Fig. 4, pulling the formed knot off the bills over the temporarily clamped tail portions thereof, and then restoring the pull-off arm to its full-line position during the following idle movement of 75 the bills.

It will be understood that the pull-off arm, acting on the main portions of the two knotted strands, tends to pull the knot together and tighten it. In this operation of tightening the knot, the 10 present invention provides for spreading the main portions of the two strands materially farther apart than their relatively close relation which they occupied in the slots 197 and 199, so as to increase the angle between them and the effectiveness with which tension in the strands pulls the parts of the knot together. Thus, the pull-off arm 160 is shown as provided with a humped portion 160^a adapted to enter in between the two strands and having downwardly slanting sides, 20 with the effect of exerting a camming action on the two strands such as to spread them and increase the angle between them as they are lifted out of the slots 197 and 199. The result of this action is to pull the portions of the knot together 25 more positively and securely than would be the case if, in tightening, the strands were maintained in about the relative positions determined by the slots 197 and 199.

It should be understood that the present disclosure is for the purpose of illustration only and that this invention includes all modifications and equivalents which fall within the scope of the appended claims.

I claim:

1. A knot tier having therein a pair of rotary bills, means for receiving and holding separately two strands respectively at one side of each bill, and guide means for the strands on the other side of each bill, said guide means including 40 shoulder portions beneath which the strands can lie whereby to retain the strands in operative relation to the bills.

2. A knot tier having therein a pair of rotary bills, means for receiving and holding separately two strands respectively at one side of each bill, and a divider element located at the other side of each bill in position to keep the strands separate, said divider element having shoulders adapted to 45 retain the strands in operative relation to the 50 bills.

3. A strand-uniting mechanism having therein a pair of rotary bills, a smooth guiding element along which one strand is adapted to slide toward the path of rotation of one bill, the knoter 55 being provided with a slot into which said strand is adapted to drop in position to be acted on by the last-mentioned bill, and means for receiving and holding another strand separately from the aforesaid strand, and crossing mechanism operating on the two separate strands in conjunction with the bills.

4. A strand-uniting mechanism having therein loop-forming and strand-severing means, means for automatically delivering pairs of strands to 65 the loop-forming and strand-severing means, means for receiving and holding separately the two strands thus delivered, and means operating in timed relation to the loop-forming and strand-severing means to cross the two separately held 70 strands.

5. A strand uniting mechanism including a rotary tying bill mechanism, means for automatically delivering pairs of strands separately to the tying bill mechanism, means for receiving and 75

- holding separately the two strands thus delivered, means for positioning the strands for knotting by the rotation of the tying bill mechanism, and means for actuating the tying bill mechanism.
- 5 6. Strand-uniting mechanism including a pair of rotary bills each including means for severing a strand, means for automatically delivering pairs of strands separately to the bills, means for receiving and separately holding the two strands thus delivered, means for positioning the strands for knotting by the rotation of the bills, and means for rotating the bills to form a knot in the strands.
- 10 7. A knot tier having therein a pair of cooperating rotary bills each including means for severing a strand, means for holding two strands to be knotted by said bills, and means for pulling the two strands to tighten the knot formed by the bills, said pulling means including a cam element shaped to spread the main portions of the two strands apart during the action of the said pulling means.
- 15 8. A knot tier having therein a pair of bills rotatable about a common axis, a main driving shaft parallel with the axis of rotation of the bills, driving connections from the shaft to the bills, a side plate stationarily mounted with respect to the axis of rotation of said bills, strand-crossing linkage, a pull-off arm mounted on said side plate to move in planes substantially parallel to said plate, and cam means on said shaft for operating the strand-crossing linkage and pull-off arm.
- 20 9. A knot tier having therein a pair of bills rotatable about a common axis, a main driving shaft parallel with the axis of rotation of the bills, driving connections from the shaft to the bills, a side plate stationarily mounted with respect to the axis of said bills, a pull-off arm pivotally mounted on the side plate, and cam means for operating said arm from said shaft.
- 25 10. Strand-crossing mechanism having therein a pair of bills rotatable about a common axis, means for arranging the strands in the paths of said bills so that each bill in rotating forms a loop of a strand which is bent about the opposite bill, and a guide element between the bills in a part of their path of rotation acting on the parts of strands extending across from one bill to the other to define their positions with relation to the axis of rotation of the bills.
- 30 11. Strand-uniting mechanism having therein a knotter including an actuating shaft therefor, a constantly moving driving member, means hav-
- ing frictional engagement with the constantly moving driving member for imparting its movement to the knotter-actuating shaft, and means for restraining the knotter shaft from rotation, said last-named means being releasable to permit the knotter shaft to be rotated.
- 35 12. Strand-uniting mechanism having therein a knotter including an actuating shaft therefor, a constantly moving driving member, means having frictional engagement with the constantly moving driving member for imparting its movement to the knotter-actuating shaft, and a latch adapted to cooperate with said last-named means to stop its rotation at the end of one revolution, whereby tripping the latch causes the knotter shaft to be rotated one revolution and then stop.
- 40 13. A knotter having therein a U-shaped frame member, a main shaft mounted in the side elements of said U-shaped frame member, a pair of rotary bills mounted one in each of said side elements and directed toward one another, means for driving the bills from the shaft, a plate mounted perpendicular to said side elements, strand-crossing mechanism and a pull-off arm mounted on the plate, and cam means on said shaft for operating the strand-crossing mechanism and pull-off arm.
- 45 14. A knotter having therein a main shaft, a pair of rotary bills, gearing between the bills and shaft adapted to rotate the bills two full revolutions during one revolution of the shaft, strand-crossing mechanism and a pull-off arm, and cam means rotated by said shaft to impart a single cycle of operation to said crossing mechanism and pull-off arm during one revolution of the shaft, whereby at the end of one full revolution of the shaft the bills, crossing mechanism and pull-off arm are in the same position as before said revolution of the shaft.
- 50 15. A knotter having therein a main shaft, a pair of rotary bills, gearing between the bills and shaft adapted to rotate the bills two full revolutions during one revolution of the shaft, strand-crossing mechanism and a pull-off arm, cam means rotated by said shaft to impart a single cycle of operation to said crossing mechanism and pull-off arm during one revolution of the shaft, whereby at the end of one full revolution of the shaft the bills, crossing mechanism and pull-off arm are in the same position as before said revolution of the shaft, and means for detaining the shaft against further revolution at the end of one full revolution.

EDWARD J. ABBOTT.
